CABINET STOVE

Filed May 18, 1928

Inventor:
Edward C. Hoffmann,
by Harry Klingland.
His Attorney.

UNITED STATES PATENT OFFICE.

EDWARD C. HOFFMANN, OF BEAVER DAM, WISCONSIN.

DESIGN FOR A CABINET STOVE.

Application filed May 18, 1928. Serial No. 26,743. Term of patent 14 years.

To all whom it may concern:

Be it known that I, EDWARD C. HOFFMANN, a citizen of the United States, residing at Beaver Dam, in the county of Dodge and State of Wisconsin, have invented a new, original, and ornamental Design for Cabinet Stove, of which the following is a specification, reference being had to the accompanying drawing, forming part thereof.

The figure is a perspective of the cabinet stove showing my new design.

I claim:

The ornamental design for a cabinet stove, as shown.

EDWARD C. HOFFMANN.
